UNITED STATES PATENT OFFICE.

FRANCIS G. GALE, OF WATERVILLE, QUEBEC, CANADA.

MATTRESS FRAME.

1,419,727.

Specification of Letters Patent. Patented June 13, 1922.

Application filed August 19, 1919. Serial No. 318,509.

To all whom it may concern:

Be it known that I, FRANCIS G. GALE, a subject of the King of Great Britain, residing at Waterville, Province of Quebec, Dominion of Canada, have invented an Improvement in Mattress Frames, of which the following description, in connection with the accompanying drawing, is a specification, like characters on the drawing representing like parts.

This invention relates to mattress frames and particularly to the manner of connecting the side rails and the end rails. In the manufacture of mattress frames it is usual 15 to provide a corner fastening construction at each end of the side rail for connecting the side rail to the end rail, such corner fastening construction being so arranged that the end rail is supported above the side rail 20 and frequently slightly beyond the end thereof.

It is the object of my present invention to provide a novel corner fastening which can be made of sheet metal without the loss of 25 any material; which has all the necessary strength to support the end rail; which is light in weight, and which is so constructed that when it is used with tubular end rails and side rails it operates not only to connect these rails, but also to close the ends of 30 the tubes.

In order to give an understanding of my invention, I have illustrated in the drawings some selected embodiments thereof which 35 will now be described, after which the novel features will be pointed out in the appended claims.

Fig. 1 is a perspective view of a corner of a mattress frame embodying my invention 40 and having rectangular tubular side and end rails;

Fig. 2 is a section on the line 2—2; Fig. 1;

Fig. 3 is a section on the line 3—3, Fig. 1;

Fig. 4 is a view of the sheet metal blank 45 from which the corner fastening is made;

Fig. 5 is an end view of the mattress frame corner shown in Fig. 1;

Fig. 6 is a side view of said mattress frame corner;

Fig. 7 is a side view of a mattress frame 50 embodying my invention and having cylindrical tubular side rails;

Fig. 8 is an end view of Fig. 7;

Fig. 9 is a view of the blank from which 55 the fastening shown in Figs. 7 and 8 is made.

In the drawings I have illustrated one corner only of a mattress frame as this is sufficient to give an understanding of the invention.

My improved corner fastening may be used in mattress frames having side and end rails of various shapes.

I have illustrated herein the invention as it would be embodied in mattress frames having tubular side and end rails, and in Figs. 1 to 6 I have shown a mattress frame in which the tubular side and end rails are rectangular in cross-section and in Figs. 7 and 8 I have illustrated a mattress frame in which the tubular side rails are circular in cross-section.

Referring to Figs. 1 to 6, 1 indicates the end of a tubular side rail and 2 indicates one end of a tubular end rail, both of said tubular rails being rectangular in cross-section so that each presents opposite flat sides.

The corner fastening is indicated generally at 3 and it is made from a sheet metal blank which will preferably have the shape shown in Fig. 4, said blank being narrower at one end than at the other and having one side edge 10 at right angles to the bottom edge 11 and having the other side edge 12 inclined to the bottom edge. This sheet metal blank is bent transversely along the dotted line 6 so as to provide the lip or flange portion 5 which extends at right angles to the body and is also bent along the inclined dotted line 7 so that the portion 8 thereof will stand at right angles to the body of the blank.

In securing the corner fastening to the rails 1 and 2 said fastening is placed against the end of the rail 2 with the bent-over portion 5 overlying the top of the rail, as shown in Fig. 1, so that the end of the rail is closed by said fastening, and the latter is then secured to the rail 2 either by means of rivets 9 which extend through the bent-over portion 5 and the tubular end rail, as shown in Fig. 2, or by welding the portion 5 to the end rail. The lower end of the corner fastening is secured to the end of the side rail 1 in the manner shown in Figs. 1 and 3, that is, said side rail and corner fastening are assembled so that the lower end of the corner fastening overlies the outer face of the side rail and the end of the side rail abuts against the portion 8 of the fastening, said portion being made wide enough to completely cover the end of the side rail. The

corner fastening and side rail may be secured rigidly together by means of rivets 13 or by being welded together as desired. Since the line 7 on which the portion 8 is bent is inclined with reference to the base 11, said portion 8 will have an inclined position relative to said base 11. The end of the side rail 1 is cut so as to fit squarely against the portion 8 and thus said portion 8 serves 10 to close completely the end of the tubular side rail. The corner fastening thus operates to close completely the ends of both the tubular rails 1 and 2.

The use of tubular rails is advantageous 15 because they are light and yet strong, and by means of them a light weight mattress frame can be produced, but where tubular rails are used it is important that the ends should be closed, for otherwise open spaces 20 are provided for harboring vermin. The construction herein shown has the advantage that it enables the use of tubular side and end rails and at the same time provides a construction by which the ends of the rails 25 are closed, thus eliminating any possible cracks or crevices in which vermin might gather.

Since the side 12 and the line 7 along 30 which the corner fastening is bent are both inclined to the base 11, the result will be that the end rail 2 will be situated slightly beyond the end of the side rail 1 which is a desideratum in mattress frames. Furthermore, in the completed mattress frame the 35 lower edge 14 of the portion 8 is longer than the width of the side rail 1 and hence said portion extends inwardly beyond the side rail, thus making a desirable added support to rest on the bed frame.

40 In Figs. 7 and 8 I have illustrated my invention as it might be applied to a mattress frame in which the tubular side rail is cylindrical in shape and the tubular end rail is rectangular in shape. In this construction the fastening which is indicated at 30 45 is secured to the rectangular end rail 2 in the same manner as illustrated in Figs. 1 to 6. In Figs. 7 and 8, however, the side rail 31 is shown as circular in cross section, 50 and in this embodiment the fastening 30 will be formed from a blank shown in Fig. 9 which is bent along the dotted line 32 so as to provide the wing portion 33 that stands at right angles to the main portion 55 30. The lower end of the portion 30 over lies the side of the side rail 31 and is curved to fit the periphery of said side rail, said lower end being welded or riveted to the side rail. The bottom edge of the blank 30 60 is shaped so that when the wing 33 is bent into right-angular position relative to the body of the corner fastening, the portion 34 of the lower edge of said wing will follow

the periphery of the side rail 31 and the portion 35 of said lower edge will extend 65 tangential thereto and substantially parallel to the end rail 2. This wing 33 is of suitable dimensions so that it entirely covers the end of the side rail 31 and thus in this embodiment of my invention also the corner 70 fastening is constructed to close the end of the rails 31 and 2. In this embodiment also the corner fastening has a backward inclination relative to the side rail 31 so that the end rail will be situated beyond the end 75 of the side rail and the end of the side rail is cut at an angle to fit against the inclined wing 33, as best seen in Fig. 7.

The use of tubular side and end rails which are rectangular in cross-sectional area 80 has the advantage that tubes of lighter weight can be used without sacrificing necessary strength. In the end rail, the strain comes in a horizontal direction, and by placing this end rail with the longer diameter 85 horizontally, a rail having a relatively small vertical dimension can be employed without sacrificing any necessary strength. The strains on the side rail are in a vertical direction, and hence by placing the side rails 90 with their longer diameters in a vertical direction the necessary strength is secured, even though the side rail has a relatively small horizontal dimension.

I claim:

1. In a mattress frame, the combination with a flat-sided tubular end rail, of a flat-sided tubular side rail, and a corner fastening member made of sheet metal which is bent to form three portions, each situated 100 at right angles to the other, one portion overlying and secured to the side of the end rail, another portion closing the open end of said end rail and overlying and being secured to the side of the side rail, and the other portion closing the open end of the side rail.

2. In a mattress frame, the combination with a tubular side rail rectangular in cross section with its longer dimension in a vertical direction, of a tubular end rail also rectangular in cross section but with its longer dimension in a horizontal direction, and a corner fastening member of sheet metal which is bent to form three portions at right angles to each other, one portion being secured to the side of the side rail and closing the open end of the end rail, another portion closing completely the open end of the side rail, and the third portion overlying and being secured to the side of the end rail.

In testimony whereof, I have signed my name to this specification.

FRANCIS G. GALE.
